UNITED STATES PATENT OFFICE

154,417

DESIGN FOR A TABLE KNIFE OR SIMILAR ARTICLE

James P. Morgan, Gardner, Mass., assignor to Frank Smith Silver Company, Gardner, Mass.,
a corporation of Massachusetts

Application May 12, 1948, Serial No. 146,314

Term of patent 14 years

(Cl. D54—12)

To all whom it may concern:

Be it known that James P. Morgan, a citizen of the United States, residing at Gardner, in the county of Worcester and State of Massachusetts, has invented a new, original, and ornamental Design for a Table Knife or Similar Article, of which the following is a specification, reference being had to the accompanying drawing, forming part thereof.

Fig. 1 is a front elevational view of a table knife;

Fig. 2 is an elevational view of the cutting edge of the same; and

Fig. 3 is a rear elevational view thereof, showing my new design.

I claim:

The ornamental design for a table knife or similar article, substantially as shown.

JAMES P. MORGAN.
